CLAIM

The ornamental design for a jersey style decorative cover for a slow cooker, as shown and described.

DESCRIPTION

FIG. 1 is an elevational view of the jersey style decorative cover for a slow cooker according to the present design.

FIG. 2 is a front plan view of the present design;

FIG. 3 is a top plan view of the present design;

FIG. 4 is a rear plan view of the present design;

FIG. 5 is a bottom plan view of the present design;

FIG. 6 is a right side plan view of the present design; and, FIG. 7 is a left side plan view of the present design.

The broken lines shown are for environmental purposes only and form no part of the claimed design.

1 Claim, 4 Drawing Sheets
